ELECTRICAL CONNECTOR PRIMARILY INTENDED FOR CONNECTION TO A DUAL-IN-LINE INTEGRATED CIRCUIT

Ronald Henry Trickey, Hoddesdon, Hertfordshire, England, assignor to Electrosil Limited, Sunderland, England

Filed May 23, 1969, Ser. No. 17,307

Claims priority, application Great Britain Nov. 29, 1968

Term of patent 7 years

Int. Cl. D13—03

U.S. Cl. D26—1

FIG.1

FIG.2

FIG.3

FIG. 4

FIG. 5

FIG. 1 illustrates the side view of an electrical female connector primarily intended for connection to a dual-in-line integrated circuit and having at each end a pivotally mounted clip.

FIG. 2 illustrates an end view of the connector, showing one of the two clips, a recess extending the length of the body of the connector and two rows of terminations, one row of which is seen in FIG. 1.

FIG. 3 illustrates a top plan view of the connector showing the two rows of terminations and the two clips.

FIG. 4 is an under plan view showing the recess, and, on each side of the recess, a row of projections between each adjacent pair of which is a cavity containing a contact connected to a corresponding one of the terminations.

FIG. 5 is a cross-section of the line 5-5 of FIG. 3 showing the form of the clips and one row of projections and contacts at one side of the recess.

I claim:

The ornamental design of an electrical connector primarily intended for connection to a dual-in-line integrated circuit, as shown and described.
